PRODUCING SOUND RECORDS IN
HALF-WAVE RECORDSCarlheinz Becker, Berlin-Wilmersdorf, Germany;
vested in the Alien Property CustodianApplication August 27, 1940, Serial No. 354,459
In Germany March 18, 1939

1 Claim. (Cl. 179—171)

The present invention relates to sound recording and, particularly, to the making of half-wave records which are referred to as push-pull class B records.

An object of the invention is to avoid disturbances and distortions which previously occurred when the alternating current is divided into two half waves.

Other objects and advantages will be apparent from the following description of detailed embodiments of the invention, when read in connection with the accompanying drawings, in which:

Fig. 1 shows a circuit for producing half-wave records, and Figs. 2 to 6 show different embodiments of the invention wherein the disturbances and distortions are avoided.

Referring to the left-hand side of Fig. 1, the previously amplified microphone voltage is applied across a resistance unit 1 which is connected between the cathode and grid of an amplifier tube 2. The cathode-anode circuit of tube 2 is formed by a battery 3 and the primary winding 4 of a push-pull transformer having two secondary windings 5 and 6. Winding 5 is connected across a resistance 9 with one side being connected through a diode 7; similarly, winding 6 is connected through a diode 8 across a resistance 10. The diodes allow currents to pass in one direction only with the result that, during one half of each cycle, current flows from winding 5 through diode 7 and resistance 9; and, during the other half of each cycle, current flows from winding 6 through diode 8 and resistance 10. This produces one-half wave voltages across resistances 9 and 10 which are supplied to the recording mechanism.

It has been found that this arrangement for producing sound recordings in half-wave records has the following disadvantages:

At each reversal of the current flow through the transformer, the diodes 7 and 8 operate in such a manner that one of the push-pull circuits is cut in and the other is cut out. Due to the fact that substantial power is required for operating the recording mechanism, considerable current flows with the result that the effect of cutting in and cutting out the circuits is appreciable. In each of windings 5 and 6, the self-induction tends to cause disturbances in the push-pull circuit itself as well as through a reactive effect in the other push-pull circuit. These various disturbances distort the sound record to an extent that the record is at times rendered useless.

In the embodiment of Fig. 2, an electric balance is provided for a circuit such as that shown in

Fig. 1. Here, the transformer is designated at 3. Each push-pull circuit is provided with a second parallel circuit, there being a circuit formed by diode 7' and a resistance 9' connected in parallel with the circuit of resistance 9 and diode 7 and there being similarly a circuit formed by a diode 8' and a resistance 10' which is connected in parallel with the circuit of resistance 10 and diode 8. From an electrical standpoint, diodes 7 and 7' and resistances 9 and 9' are similar and the diodes are connected in an opposite sense so that current flows through diode 7' when no current flows through diode 7. Diodes 8 and 8' and resistances 10 and 10' are similarly related. During operation, the auxiliary parallel circuits formed by diodes 7' and resistance 9' and diode 8' and resistance 10' respectively draw current from their respective windings.

In the embodiment of Fig. 3, the two push-pull circuits are supplied through separate transformers 3 and 3', respectively, transformer 3' having a primary winding 4'. Primary winding 4 receives current through tube 2 and primary winding 4' receives current through a similar tube 2'. By this arrangement, the change of current in one of the secondary windings does not effect the other transformer. In this way, the major source of the distortion is eliminated.

The further modification of Fig. 4 avoids the disturbances by the connection of the diode circuits. As indicated above in connection with the discussion of Fig. 1, the disturbances and distortions depend in part on the intensity of the current flowing in the push-pull circuits and it is desirable to maintain these currents as small as possible. However, due to the fact that considerable power is required to operate the recording of the mechanisms which are connected to resistances 9 and 10, it is desirable that these currents be large and in the embodiment of Fig. 4 very high ohmic values are chosen for resistances 9 and 10 with the result that small currents flow through these resistances and no substantial distortion or disturbance results. Resistance 9 is connected across the cathode-grid circuit of an amplifier tube 11, the cathode-anode circuit of which is connected to a battery across a resistance 13; similarly, resistance 10 is connected across the cathode-grid circuit of an amplifier tube 12 which has its cathode-anode circuit connected through the battery across resistance 14. Changes in voltage across each of the resistances 9 and 10 cause corresponding changes in the voltage across the respective resistances 13 or 14, and sufficient power is available from the circuits of

tubes 11 and 12 to operate the recording mechanism.

Due to the characteristics of the diodes, when the amplitude is small, no half-wave record (push-pull class A or class AB record) is obtained. The reason for this is that the characteristics of the diodes do not pass through the zero point, there being currents of small amplitude which flow in the reverse direction through the push-pull circuits.

This defect is avoided in accordance with the present invention by inserting in each of the diode circuits an adjustable negative counter-voltage which is of such a value that the effective operating characteristics of the diode pass through the zero point.

Referring to Fig. 5, the common line between the push-pull circuits is provided with a counter voltage unit. This unit is formed by potentiometer 16 which has connected across its ends a battery 16. By adjusting the contact on the potentiometer, the proper voltage is placed in series in the diode circuit so that the effective operating characteristics of the diodes 7 and 8 pass through zero. In this way, the diodes allow a flow of current in one direction only.

In making records, it is necessary to supervise the half-wave voltages which are impressed upon the recording device. In the illustrative embodiment of the invention represented in Fig. 6, the two half waves are composed into a complete curve again and the resultant voltage is supplied by way of an amplifier to a control member such as a Braun tube or a loud speaker. This composition is effected in a simple manner by providing a circuit such as described above and the including in each of the push-pull circuits a take-off circuit parallel to the output from which the half-wave is impressed upon an amplifier circuit. Referring particularly to Fig. 6, the recording members are supplied with half-wave voltages

either at resistances 9 and 10 or at resistances 17 and 18. Voltages for control purposes are taken off through condensers 22 and are impressed upon the grids of tubes 19 and 20 which are arranged in push-pull fashion. The two anodes of tubes 19 and 20 are connected to the opposite ends of the primary windings of transformer 21 and the center tap is connected to one side of the battery. The other side of the battery is connected to the cathodes of the two tubes and also to the common line of the resistances 9 and 10. The secondary winding of transformer 21 is connected to the control member. During operation, the half-wave voltages which occur at resistances 17 and 18 are displaced 180° and the half-wave voltages occurring at the resistances 9 and 10 respectively, and the voltages applied to the grids of tubes 19 and 20 form a complete wave. Condensers 22 are similar in their characteristics so that voltages of equal magnitude are tapped from resistances 17 and 18 and resistances 9 and 10.

What I claim is:

In a push-pull amplifying circuit of the type including a transformer having its primary connected to a source of speech currents and its divided secondary applied symmetrically in push-pull coupling to a pair of rectifier tubes and loading resistors in series connection therewith, whereby a half-wave signal appears across one of the loading resistors and the corresponding half-wave signal of opposite polarity appears across the other loading resistor, means for reducing distortion during amplification, said means comprising a shunt circuit consisting of a rectifier and a loading resistor connected across each half of the divided secondary, whereby currents of opposite polarity to the half-wave signal are dissipated in the resistor which forms a part of the shunt circuit.

CARLHEINZ BECKER.
